Primary Examiner — Messina L Smith*Assistant Examiner* — Carolyn W Davis(74) *Attorney, Agent, or Firm* — Fish & Richardson P.C.(57) **CLAIM**

The ornamental design for a coupling as shown and described.

DESCRIPTION

FIG. 1 is perspective view of a coupling according to my new design.

FIG. 2 is a side view of the coupling; and,
FIG. 3 is an end view of the coupling.

The dashed broken lines in the drawing depict portions of the coupling that form no part of the claim. The dash-dot broken lines define the boundaries of the claim and form no part thereof.
